UNITED STATES PATENT OFFICE.

JOHN GOOD, OF BROOKLYN, NEW YORK.

INTERNAL-COMBUSTION ENGINE.

1,171,427.

Specification of Letters Patent. Patented Feb. 15, 1916.

Application filed January 7, 1914. Serial No. 810,721.

To all whom it may concern:

Be it known that I, JOHN GOOD, a citizen of the United States, and a resident of Brooklyn, in the county of Kings and State 5 of New York, have invented the following described new and useful Improvements in Internal-Combustion Engines.

This invention is an improvement in the valve arrangement of internal combustion 10 engines and particularly multi-cylinder engines in which rotary disks or labyrinth valves are employed for controlling the intake and exhaust, all as hereinafter explained and more particularly pointed out 15 in the accompanying claims.

In the drawings forming part hereof, Figure 1 is a top plan view of an engine embodying the invention, with parts broken out to illustrate interior construction. Fig. 20 2 is a side elevation of the same structure partly in section. Fig. 3 is an end elevation with parts in section. Fig. 4 is a cross section through one of the cylinder heads on larger scale. Fig. 5 is a detail of one of the 25 shaft-borne disks; and Fig. 6 a similar detail of one of the stationary or port disks.

The multi-cylinder engine shown comprises a water-jacketed body structure 1, containing four or any desired number of 30 cylinders cast *en bloc* or otherwise, and attached to any suitable base casting, as shown in Fig. 3, with which it may form a crank case. The head structure for the several cylinders may be formed of one or 35 several castings and may be integral with the body casting if desired, according to the particular design. It is shown herein as a single casting, in which are contained the inlet and exhaust passages for each cylinder 40 as well as the valves therefor, the shafts for such valves and other parts later described. The inlet and exhaust passages are arranged on opposite sides of the head structure and connected with the intake and exhaust 45 manifolds which run alongside of the upper portions of the cylinders proper, parallel with the row of cylinders. Either manifold may serve as inlet or exhaust according to preference. In the drawings the 50 manifold marked 2, may be assumed to be the intake and the passage 3 the inlet passage, connecting the same with the cylinders, 5 being the corresponding exhaust passage 55 and 6 the exhaust manifold connecting therewith. Each cylinder has a similar arrangement of intake and exhaust passages and

connections with the manifolds. The inlet and exhaust valves of each cylinder may be of identical formation and each is constituted in the present case by a series of fixed 60 disks 7 having port openings 7^a (Fig. 6), and a complementary series of interlapping rotary disks 8, which have ported openings 8^a (Fig. 5). The fixed disks 7 are secured in the head structure with their openings 7^a 65 in alignment with each other and also in alignment with the inlet or exhaust passage 5 or 4, and they are spaced from each other by a series of interposed rings 9, and kept in alignment by means of a key 10. The rotary 70 disks 8 are similarly keyed to the valve shaft 4, with their openings 8^a in alignment, being spaced from each other by the interposed washers 11. The thickness of the washers 11 and spacer rings 9, is so proportioned 75 with respect to the thickness of the disks as to prevent substantial contact between the fixed disks and the rotary ones, thus forming a crevice of labyrinthic character 80 through the set of interlapping disks, substantially as indicated in Fig. 4. When the port openings in the shaft-borne disks are in alignment with the openings in the fixed or port disks, the valve presents a free passage through it, for the escape or intake of 85 gases, but when rotated to some other position in which the openings are out of alignment, the passageway through the valve is closed, notwithstanding that the fixed and movable disks are not in contact. Valve 90 structures of this kind are described in a co-pending application filed June 28th, 1913, and are not necessary to be described herein further than to say that the resistance arising from the surface friction in the narrow 95 crevice against the sides and around the edges of the interlapping disks, is sufficient to confine the combustion pressure, the obstruction to flow being increased by the 100 rotary motion of the valve disks. Such motion serves to drag the film of gaseous fluid adhering to the disks so as to compel it to travel in a direction other than that in which the leakage would naturally tend to flow if the disks were stationary, thereby compelling 105 the fluid to travel a long and tortuous path before it can escape, which results in an effectual closure of the valve passage for all practical purposes.

Both the inlet and exhaust valve of each 110 cylinder are mounted on the same transverse valve shaft by which the one is connected to

the other, and with the valve members equally exposed to the combustion pressure in opposite directions any possible tendency to endwise movement is prevented. But in order that the shaft-borne disks shall be kept permanently in an approximately centralized position with respect to the fixed disks, and out of substantial contact therewith, they are firmly clamped on the shaft 10 with their spacing washers 11 between them, by means of the nuts 12, and the shaft bearings 13 are disposed outside of the nuts at each end of the shaft, with provisions for controlling the endwise position of the latter independently of the valve members themselves. Such provisions include a collar 15 clamped by a nut 17 on the reduced end of the shaft, against a set of thin plates or washers 16, and held against the end of 20 the adjacent shaft bearing 13, or some equivalent fixed support. The number and thickness of the plates 16 are selected so that when the collar as thus clamped on the end of the shaft is contiguous to the bearing, the disks 8 will then be approximately centralized in the spaces between the fixed disks 7 of both valves. As the rubbing faces of the collar 15 and the bearing 13 become worn, the number or thickness of the plates 30 16 can be varied accordingly to preserve the centralized position, or other means of endwise adjustment may be provided. The collar for example could be threaded to the shaft. In the present case, the collar 15 is held in fixed position by means of a thrust-ring 18, and a small spring 19 interposed between the same and a split and threaded housing 20. The thrust-ring 18 is splined to the housing, and when the latter is properly adjusted the spring presses the ring against the collar 15 and the latter against the end of the bearing. It is a peculiarity of valves of the kind referred to that they are subject to no appreciable increase in 45 load or resistance to movement even when serving very high cylinder pressures, and the slight retarding action produced by the spring and thrust-ring upon the collar 15, is therefore beneficial as it serves as a brake 50 to keep the driving gears free from backlash and hence silent. At the opposite end each valve shaft is provided with a skew gear 14 by which it is driven.

In assembling the structure above described, the valve shaft 4 is first placed in position in the head structure, being passed through tube 34 in the waterjacketed part thereof, and the alternating set of disks 7 and 8, with their respective rings and washers in proper sequence, are then placed in position. There is one shaft for each cylinder extending transverse to the cylinder axis and also to the axis of the engine as a whole. The shaft-borne disks are then 65 clamped in place by their nuts 12 and the

fixed disks by means of the cover plates 21 and 22, which are bolted to the main casting of the head structure. The collar 15 is then applied to the end of the shaft with the appropriate number of interposed spacing washers 16, and the housing 20 is then applied to the hub of the cover plate 21 and screwed up until the friction on the collar is sufficient to keep the gearing silent. Each of the four crosswise valve shafts 4, is similarly mounted and each receives a similar skew gear 14 at its end, the latter gears being preferably all on the same side of the row of cylinders and all driven by a common shaft 24, through complementary skew gears 23 thereon. The common drive shaft is carried by the head structure of the engine, in the present case, being journaled in the horizontal bearings 24^a (Fig. 2) so that it extends adjacent to the head structure and parallel with the row of cylinders. At one end this shaft is fast to a skew gear 25 meshing with a complementary skew gear 26 on an oblique shaft 27, and the latter shaft is driven from the engine crank shaft 28 by the skew gears 29. (See Figs. 2 and 3). It will be understood that the various sets of valve disks are so placed on their respective transverse valve shafts 4 as to open and close the inlet and exhaust ports of the several cylinders in a proper sequence and according to the arrangement of the cranks (not shown) on the engine crank shaft.

The cover plates 22 of the head structure, besides serving as the clamping means for the fixed disks 7 and the bearings for the ends of the valve shafts, are also utilized to form portions of the housings for the gears 14 and 23, the balance of such housings being provided by separate casings 30, as shown more clearly in Fig. 4. The cover plates 22 also provide the bearings 24^a, above referred to, and a portion of any two of such cover plates and the casings 30 may be combined to form a pump casing, as indicated at 31 in the drawings. The terminal cover plate also provides a support, such as indicated at 32, for a magneto generator, commutator or other engine appurtenance. The water connections for the head structure are not indicated. With these casings on one side and the housings 20 on the other, the whole of the valve gearing is completely inclosed.

Between the side portions containing the labyrinth valves, the head structure is longitudinally depressed from end to end, the bottom of the depressed portion being at different levels. The parts of the lowest level, marked 35, are so arranged that one of them is common to two adjacent cylinders and two spark plug holes are drilled therein to receive the spark plug (or fuel injector) for each of such cylinders. The depressed portions 36 serve to inclose the central por-

tion of the rotary valve shafts 3 forming the water jacket which surrounds them as shown in Fig. 2.

I claim:

5. 1. A multi-cylinder combustion engine having rotary multiple disk intake and exhaust valves rotating on axes which are transverse to their respective cylinder axes and also transverse to the row of cylinders, 45
10 intake and exhaust ports controlled by said rotary valves and disposed on opposite sides of the cylinder axes, respectively, a common drive-shaft for all of said valves, and gear means connecting the shaft with the engine 15 crank-shaft.
2. In a combustion engine, a plurality of cylinders each having a rotary valve-shaft disposed transversely to its cylinder axis and also to the row of cylinders, a pair of rotary multiple disk valve-members secured to each shaft, the members of each pair being exposed to the combustion pressure of its cylinder in opposite directions, and a common drive-shaft for all the said valve- 25 shafts.
3. In a combustion engine, a plurality of cylinders, a valve-shaft for each cylinder journaled transversely thereof and also transversely of the row of cylinders, oppositely disposed intake and exhaust valves mechanically connected to each other by the valve-shaft and respectively exposed in opposite directions to the combustion pressure, 30 a gear on each of the valve-shafts, a common drive-shaft engaging said gears and means independent of the valve members for adjusting said valve shafts in an endwise direction.
4. In a combustion engine, a row of cylinders each having a valve-shaft carrying a series of disks and rotating on axes and also 35 to the row of cylinders transverse to their cylinder axes, a series of port disks interlapping with the shaft disks and forming a valve therewith, a longitudinal drive-shaft 45 geared to each of the valve-shafts for operating the respective disks thereof, and a gear means for operating the drive-shaft from the engine crank-shaft.
5. In a combustion engine, a row of cylinders, a valve-shaft for each cylinder having a series of disks thereon, and journaled at the head of each cylinder to rotate on axes transverse to the cylinder and to the row of cylinders, in combination with a complementary series of disks for each series of shaft-borne disks, interlapping but not contacting therewith, a longitudinal drive-shaft on one side of the cylinder geared to each valve-shaft thereof and driven by the engine 60 crank-shaft, and means independent of the drive shaft for adjusting the valve shafts in an endwise direction.
6. In a multi-cylinder engine, a series of engine cylinders having inlet and exhaust ports on opposite sides controlled by rotary multiple disk valves, a transversely journaled valve shaft for each cylinder by which the valves thereof are actuated, and a head structure for the cylinders in which said valves and shafts are contained, the said head structure having depressions between the shafts and spark plug holes formed in said depressions.

In testimony whereof, I have signed this specification in the presence of two witnesses.

JOHN GOOD
